UNITED STATES PATENT OFFICE.

JAMES LEVER RUSHTON, OF BOLTON, ENGLAND.

DRAWING MECHANISM FOR RING-SPINNING FRAMES AND THE LIKE.

Application filed May 10, 1924. Serial No. 712,205.

To all whom it may concern:

Be it known that I, JAMES LEVER RUSHTON, a subject of the King of Great Britain, residing at Kay Street Works, Bolton, in the county of Lancaster, England, have invented new and useful Improvements in Drawing Mechanism for Ring-Spinning Frames and the like, of which the following is a specification.

10 The invention relates to improvements in or relating to drawing mechanism for ring spinning frames, draw frames and the like and has for its object to provide an improved arrangement of rollers whereby yarn can be spun having a higher draft than hitherto while being free from irregularities due to differences in the lengths of the fibres or other causes.

For the purpose of this invention the usual roller stand is provided with a front bottom fluted roller having a suitable flannel-covered clearer roller, a back bottom plain roller and a back top weighting roller.

Mounted upon the roller stand between the back and front rollers is a flat board or the like whose surface is aligned with the tops of the said two rollers, and passed around said back bottom roller and the said board is an endless band or belt of leather or other suitable material, said endless belt being maintained taut by means of a shoe hinged to the underside of the board and pressed against said endless belt by a suitably mounted spring.

35 Mounted in slots in the cap bars is a hollow middle roller adapted to rest upon the endless belt, and likewise mounted and adapted to rest upon the endless belt at or near to the lower edge of the flat board said lower edge being suitably curved, is a roller covered with rubber, leather or other suitable material.

Also carried by the cap bars and adapted to press against the front bottom fluted roller is a leather-covered front top roller, which is provided with a flannel-covered top clearer roller adapted to rest upon said front top roller and the back top weighting roller hereinbefore mentioned.

50 In a modification of the device the means for maintaining the endless strip taut, comprising a spring-controlled shoe, are sub-

stituted by a weighted lever pivotally mounted upon a rod extending from roller stand to roller stand one end of said lever being adapted to bear against the underside of the endless belt and by reason of the lever being weighted said endless strip is maintained taut thereby, while suitable flanges formed upon said lever serve to maintain the lever in its correct position relative to the band.

And in order that the said invention may be more clearly understood and readily carried into effect, I will now proceed more fully to describe the same aided by the accompanying drawings in which—

Figure 1 is a section of the drawing mechanism of a ring spinning frame constructed according to the present invention.

Figure 2 is a plan thereof, the back top weighting roller, the leather-covered front top roller and the top flannel-covered clearer roller being removed.

Figure 3 is a plan thereof of the said top rollers however being replaced.

Figure 4 is a section of a modification thereof, and

Figure 5 is a front and side elevation of the weighted lever employed to maintain the endless strip taut.

Referring to Figures 1, 2 and 3, 1 represents the roller stand, 2 the cap bar pivotally mounted thereon at 3, 4 the roving guide and 5 the thread guide mounted upon the frame 6 of the machine.

7 represents the front bottom fluted roller having a flannel-covered clearer roller 8. 9 is a plain back bottom roller and mounted upon the stand 1 between the rollers 7 and 9. 10 is a flat board or the like 10, whose upper surface is aligned with the tops of said rollers 7 and 9, and passing around said back bottom roller 9 and the said board 10 is an endless band or strip 11 formed of leather or other suitable material, said endless strip 11 being maintained taut by means of a shoe 12 hinged at 12^a to the underside of the board 10 and constrained to press against said endless strip 11 by a spring 13 also mounted upon the board 10.

Mounted in the slots 2^a in the cap bars 2 is a hollow middle roller 14 adapted to rest upon the endless strip 11, and similarly

mounted and adapted to rest upon said strip 11 at or near to the suitably curved lower edge of the board 10, is a roller 15 covered with rubber, leather or other suitable material.

Also carried by the cap bars 2 and adapted to press against the front bottom fluted roller 7 is a leather-covered front top roller 16, provided with a flannel-covered clearer roller 17 adapted to rest upon said roller 16 and the back top weighting roller 18.

In operation the roving 19 passes between the endless belt 11 which is driven by the back bottom plain roller 9, and the back top weighting roller 18, and is carried by said endless belt 11 over the board 10 and beneath the hollow middle roller 14 and the leather or rubber covered roller 15, said latter rollers 14 and 15 each controlling fibres of different lengths, and after passing from the endless strip or band 11 the yarn is led between the front bottom fluted roller 7 and the front top leather-covered roller 16 which rollers 7 and 16 effect a final draft which is at this stage considerably higher than heretofore.

In Figures 4 and 5 is illustrated a modification of the device in which a lever 20 pivotally mounted upon a rod at 21 extending from roller stand to roller stand and provided at one end thereof with a weight 22 and at the other end with flanges or the like 23 is used for maintaining the belt 11 in taut condition, in place of the spring-controlled shoe 12 of Fig. 1. In this form the plate member 10^a is of slightly different form from the member 10 of Fig. 1.

As the belt 11 is driven by the roller 9, the lever 20 by reason of the weight 22 bears against the underside of said belt 11 in its passage and the flanges 23 serve to maintain the lever in its correct position relative to the belt.

The roller 9 is provided with a recessed periphery leaving flanges 9^a at the ends thereof and the periphery of the roller 18 works within said recess while the flanges of the roller 9 serve as a guide for the endless belt or band 11.

It will be understood that the diameters of the several rollers and the details of construction of the device may be varied without departing from the principle of the invention.

What I claim as my invention and desire to secure by Letters Patent is:—

1. The process for obtaining a high draft of the yarn in ring spinning frames, draw frames and the like, which consists in passing the roving between a tightly-stretched endless belt and a weighted roller, then between a hollow roller and said endless belt then between a covered roller and said belt and finally between a fluted roller

and a second covered roller, the arrangement being such that the hollow middle roller and the first covered roller each control fibres of different lengths, the final draft being effected by the fluted roller and the second covered roller substantially as herein set forth.

2. In the drawing mechanism of ring spinning frames, draw frames and the like, the combination of a front bottom fluted roller, a back bottom plain roller, a flat board mounted upon the roller-stand, the surface of said board being in alignment with the tops of said bottom rollers, an endless belt of flexible material stretched over and around said board and driven by said back bottom plain roller, means for maintaining said endless band in a taut condition, a back top weighting roller adapted to bear upon said endless belt in its contact with the back plain roller, a hollow middle roller mounted in the cap bars and adapted to bear against said endless belt a covered roller likewise mounted and adapted to bear against said endless belt adjacent to the lower edge of the board, a leather-covered top front roller in contact with the front bottom fluted roller and flannel covered clearer rollers in contact with said front top and bottom rollers respectively.

3. In the drawing mechanism of ring spinning frames and the like, the combination of a front bottom fluted roller, a back bottom plain roller, a flat board mounted upon the roller-stand, the surface of said board being in alignment with the tops of said bottom rollers, an endless belt of flexible material stretched over and around said board and driven by said back bottom plain roller, pivoted means in engagement with said belt and adapted to yieldingly maintain the same in taut condition, a back top weighting roller adapted to bear upon said endless belt and maintain it in contact with the back plain roller, a hollow middle roller disposed in position to engage said belt during its passage over said board, a top front roller provided with a covering of flexible material in contact with the front bottom fluted roller, and flannel covered clearer rollers in contact with said front top and bottom rollers respectively.

4. In the drawing mechanism of ring spinning frames and the like, the combination of a front bottom fluted roller, a back bottom plain roller, a flat board mounted upon the roller-stand, the surface of said board being in alignment with the tops of said bottom rollers, an endless belt of flexible material stretched over and around said board and driven by said back bottom plain roller, a pivoted lever in engagement with said belt, means for yieldingly retaining the lever in belt-engaging position thereby to maintain the belt in taut condition, a back

top weighting roller adapted to bear upon said endless belt and maintain it in contact with the back plain roller, a hollow middle roller disposed in position to engage said belt during its passage over said board, a top front roller provided with a covering of flexible material in contact with the front bottom fluted roller, and flannel covered clearer rollers in contact with said front top and bottom rollers respectively. ¹⁰

In testimony whereof I have signed my name to this specification.

JAMES LEVER RUSHTON.
